UNITED STATES PATENT OFFICE.

IMANUEL LAUSTER, OF AUGSBURG, GERMANY, ASSIGNOR TO VEREINIGTE MASCHINENFABRIK AUGSBURG UND MASCHINENBAUGESELLSCHAFT NÜRNBERG A. G., OF AUGSBURG, GERMANY.

FUEL-FEED GOVERNOR FOR EXPLOSIVE-ENGINES.

SPECIFICATION forming part of Letters Patent No. 729,613, dated June 2, 1903.

Application filed July 15, 1902. Serial No. 115,692. (No model.)

To all whom it may concern:

Be it known that I, IMANUEL LAUSTER, a subject of the King of Würtemberg, residing at Augsburg, in the Kingdom of Bavaria and 5 German Empire, have invented certain new and useful Improvements in Explosion-Engines, of which the following is a specification.

My invention relates to improvements in fuel-feed governors for explosive-engines in 10 which a thick liquid fuel is supplied to the explosion-chamber by means of a pump intended for high back pressures; and the object of my improvements is to provide an operating-gear for the suction-valve of said 15 pump by means of which the quantity of fuel supplied by the pump is regulated in such a manner as to correspond to the varying load of the motor or the running of the engine. I attain this object by the mechanism illustrated in the accompanying drawings, in 20 which—

Figure 1 is a vertical section of the parts of the engine embodying the invention. Fig. 2 is a front view of a modification of a certain 25 part of the operating-gear. Figs. 3 to 5 represent in section three different positions of the suction-valve, with diagrammatical views of the connections to the governor in respective conditions.

Similar letters refer to similar parts throughout the several views.

The spring-loaded suction-valve *a*, which is in any event required for the pump, is positively opened during the suction stroke by the 35 rod *b* and is maintained open during the forcing stroke until the rod *b* leaves the suction-valve. The displacement of this rod is caused by means of the pump-piston *c*, (which is driven in any convenient manner,) owing to 40 the fact that the lever *d*, which is articulated at *e* to the rod *b* and pivoted at the point *f*, which is adjustable by the governor *g* and suitable intermediate means, is also suitably connected to the pump-piston *c* at *h*.

According to the displacement of the adjustable pivot *f* toward the position *f'*, Figs. 3 to 5, or toward the position *f''* the rod *b* leaves the suction-valve either earlier or later during the forcing stroke, so that a smaller 45 or larger quantity of the volume sucked in 50

during the suction stroke flows back through the suction-valve into the reservoir *i*, and consequently a larger or smaller part is forced to the machine.

In the drawings, Figs. 3 to 5, three different 55 positions of the suction-valve are shown corresponding to the disposition of the governor with one and the same position of the downwardly-moving pump-piston *c*.

The essential feature is the adjustable 60 mounting of the lever *d* and the driving of this latter by the pump-piston *c*, owing to which the travel of the piston is transmitted in a proportionately-reduced manner to the distributing-rod *b* and from this to the suction-valve *a*. In consequence it is only necessary 65 that the displacement of *b* and the power required for this displacement should be small in the same proportion, and the displacement may be effected by the governor through the 70 aid of a system of levers *j j'*, Fig. 1, or by means of an eccentric *k* and connecting-lever, Fig. 2, while without this reduced transmission of the pump-stroke to the suction-valve the displacement of *b* would necessarily bear 75 a direct proportion to the piston-stroke, thereby necessitating a large expenditure of power for displacing *b*, and consequently considerable back pressure on the governor and defective regulation.

A further diminution of the power necessary for the displacement of the rod *b* is attained by the provision of the float *l* and the valve *m*, by means of which the level is maintained constant in the supply-reservoir *i* and 85 the employment of a stuffing-box for the distributing-rod *b* rendered unnecessary, whereby the resistance inherent to such an arrangement is also avoided. This arrangement, in addition to diminishing the power required, presents the further advantage that no failure of the pump will occur when thick liquid fuels are employed, because frictional pipe resistance during suction is not present and the suction-valve *a*, loaded with a spring *n*, no 95 longer opens automatically, but is positively opened by the novel distributing-gear. In addition this distributing-gear permits of continuous displacement by the governor either during the suction or the forcing stroke of 100

the pump. At no time is the movement of the governor impeded.

What I do claim as my invention, and desire to secure Letters Patent, is—

- 5 1. In combination in an explosive-engine, a suction-valve for the liquid fuel, a pump-piston for supplying the fuel, a lever having an adjustable pivot or fulcrum, a connection between the lever and pump-piston, means connected to said lever and adapted to operate the suction-valve, and means for adjusting the fulcrum of said lever, substantially as described.
- 10 2. In combination in an explosive-engine a suction-valve for the liquid-fuel, a pump-piston for supplying the fuel, a lever having an adjustable pivot or fulcrum, a connection between said lever and the pump-piston, a rod connected to said lever and adapted to oper-

ate the suction-valve, and means for adjusting said pivot or fulcrum, substantially as described. 20

3. In combination in an explosive-engine a suction-valve, a pump-piston, a rocking lever, a governor having a connection with said lever, a second lever having one end pivoted to said first-named lever and its other end operatively connected with the pump-piston, and means connected to the said second lever for positively operating the suction-valve, substantially as described. 25 30

In testimony whereof I have signed my name to this specification in the presence of two subscribing witnesses.

IMANUEL LAUSTER.
